UNITED STATES PATENT OFFICE.

FRANKLIN P. KISINGER AND JOSEPH W. DUNHAM, OF ENGLEWOOD, ILL.

MECHANICAL MOTOR.

SPECIFICATION forming part of Letters Patent No. 241,999, dated May 24, 1881.

Application filed April 26, 1881. (No model.)

To all whom it may concern:

Be it known that we, F. P. KISINGER and J. W. DUNHAM, citizens of the United States, residing at Englewood, in the county of Cook and State of Illinois, have invented certain new and useful Improvements in Mechanical Motors; and we do hereby declare the following to be a full, clear, and exact description of the invention, such as will enable others skilled in the art to which it appertains to make and use the same, reference being had to the accompanying drawings, and to the letters or figures of reference marked thereon, which form a part of this specification.

15 Figure 1 is a side elevation of a motor embodying our improvements. Fig. 2 is a vertical sectional view of the trip-hook, and Fig. 3 is a vertical sectional view at right angles to Fig. 2.

20 This invention has relation to mechanical motors; and it consists in the improved features of construction and combination herein-after fully described, and particularly pointed out in the claims.

25 The device is intended to be first wound up by hand, and is afterward operated by any suitable power, such as engine or horse power, as will be hereinafter explained.

Referring by letter to the accompanying 30 drawings, A designates a frame supporting the gearing.

B is a double winding-drum, having a crank, C, and a gear-wheel, D. One portion of the drum B is larger than the other.

35 E is a shaft, having gears F and G. H is another shaft, having gears I and J.

K is a shaft, having gears L and M and a friction-wheel, N.

A governor, O, is mounted on a platform, P, 40 and is connected by a miter-gear, Q, with a miter-gear, R, on a shaft, S, having a gear-wheel, T, meshing with the wheel M.

U is a rope which is wound upon the larger portion of the drum B, and runs over pulleys

45 V V' on a frame, W.

X is weight for unwinding the cord U. A second cord, Z, is connected to the smaller portion of the drum B, and is wound thereon as the cord U is unwound by the weight X.

50 The governor O, by means of the presser-

foot O' pressing upon the friction-wheel W, regulates the speed of the motor.

A track, Y, is placed at the base of the frame A, and is grooved at a to receive a double hook, b, on the trip-arm c. The trip-arm c has 55 a slotted arm, d, extending up within it, and a spring, e, for returning it to its normal position after having been displaced. Wheels f are provided at the lower end of the arm c, by means of which it is guided and permitted to travel in the track Y. The upper end of the trip-arm c is provided with a pivoted catch, g, operated by a spring, h, to return it to place, and this catch g is intended to lock the arm d until the hook b engages a bolt, i, 60 in the track Y. At the center of the track Y, in the rear of the same, is a hole, j, on each side of which is a pulley, k. The cord Z is attached to a loop at the bottom of the trip-arm c, and may run over either of these pulleys k.

An engine or a horse may be attached to the catch g, and the trip-arm drawn along the track Y. The arm will travel on the wheels until the hook d engages the bolt i, when the spring e will be retracted and the latch g released and the power thrown therefrom. As 70 soon as this occurs the springs e and h will replace the arm d.

It will be observed that when the cord Z is drawn upon it will unwind, and at the same 80 time will wind up the cord U, and the reverse will also take place after the cords are in place and the cord U once wound.

l designates a crank, slotted so as to adjust it on the shaft K, to connect the motor with a 85 pump for the purpose of pumping water into a tank at railroad-stations. A churn may be connected to this crank instead of a pump. In fact, the motor may be used for many useful purposes.

The track Y is also used to protect the trip from the weather by turning in the recess m between upper and lower flanges of the track.

Having thus fully described our invention, what we claim is—

1. In a motor, the combination of a presser-foot engaging a friction-wheel, a governor, and mechanism for operating the same, substantially as and for the purposes set forth.

2. In a motor, the combination, with the dou-

100

ble drum, cords, and weight, of the track and the trip-arm, substantially as and for the purposes set forth.

3. In a motor, the trip-arm composed of the arms *c* and *d*, the spring *e*, the hook *b*, and the pivoted catch *g*, constructed and operating substantially as and for the purpose set forth.

4. In a motor, the combination of a double drum, a trip-arm, a track, a weight, and a governor, substantially as and for the purposes set forth.

5. In a motor, a trip-arm provided with

wheels, a spring, a latch, and a double hook adapted to be connected to a winding and unwinding cord, in combination with a track provided with stops, substantially as and for the purposes set forth..

In testimony whereof we affix our signatures in presence of two witnesses.

F. P. KISINGER.
J. W. DUNHAM.
